UNITED STATES PATENT OFFICE.

SAMUEL G. GREEN, OF THE UNITED STATES ARMY.

ADJUSTABLE SHOULDER-REST.

1,357,232.

Specification of Letters Patent. Patented Nov. 2, 1920.

Application filed October 3, 1919. Serial No. 328,306.

(FILED UNDER THE ACT OF MARCH 3, 1883, 22 STAT. L. 625.)

To all whom it may concern:

Be it known that I, SAMUEL G. GREEN, captain, Ordnance Dept., U. S. Army, a citizen of the United States, stationed at 5 Washington, D. C., have invented an Improvement in Adjustable Shoulder-Rests, of which the following is a specification.

The invention described herein may be used by the Government, or any of its officers or employees in prosecution of work for 10 the Government, or by any other person in the United States, without payment of any royalty thereon.

The object of my invention is to improve 15 upon the construction of shoulder rest shown, described and claimed in my co-pending application for patent, Serial No. 295,463, filed May 7, 1919, by providing a structure which is more practical from a 20 mechanical and manufacturing standpoint, which is lighter in weight, and which possesses other advantages, as will appear hereinafter.

Specifically, the improvement resides, *inter alia*, in a shoulder rest having a lengthwise adjustable gun attaching portion, preferably comprising telescoping sections.

The improvement resides, also, in an adjustable shoulder-rest piece, slidably mounted 30 on a hollow sheet metal standard, which is shaped in a novel manner from a single piece of material and suitably secured to the gun-attaching portion.

The invention is graphically shown in the 35 accompanying drawings, which show an exemplary construction embodying the underlying principles of the invention. Like reference characters designate corresponding parts throughout the several views. Briefly 40 described:

Figure 1 is a view in side elevation of my improved shoulder-rest;

Fig. 2 is a view in section on the line 2—2,

Fig. 1;

Fig. 3 is a view in top plan of the shoulder-rest;

Fig. 4 is a fragmentary view in section, taken on the line 4—4, Fig. 1;

Fig. 5 is a detached detail view, in side 50 elevation, of the hollow standard, on

which the shoulder-rest piece is adjustably mounted;

Fig. 6 is a top plan view of said standard;

Fig. 7 is a detached detail view, in side elevation, of the shoulder-rest piece;

55

Fig. 8 is a view in top plan of the shoulder-rest piece;

Fig. 9 is a detached detail view, in side elevation, of the outer telescoping section of the gun attaching portion;

60

Fig. 10 is a similar view of the inner telescoping section; and

Fig. 11 is a collective, detail view of the supporting collar for the aforesaid gun-attaching portion, which collar is secured to 65 the shoulder-rest standard.

Referring, now, in detail to the drawings:

The gun attaching portion of the shoulder-rest comprises, in this instance, two telescoping tubular members, an outer member 70 1 and an inner member 2, whereby said portion is adjustable as to length.

The outer member (shown in detail in Fig. 9) is provided with a longitudinal slot 3, extending from one end thereof, to permit 75 of contraction of the member by suitable clamping means, comprising, in this instance, a strap 4 preferably welded to the exterior of the tube 1 and carrying a pivoted clamp screw 5, carrying a clamping 80 nut 6, whereby the tube may be clamped around a gun. The clamping means described forms no part of the present invention, since it is fully shown and described in my said co-pending application.

The tube 1 is also provided with a second longitudinal slot 7, through which projects a threaded clamp bolt 8, which passes, also, through an aperture 9 in the inner tube 2. On the bolt 8 is screwed a wing nut 10. Between the nut and the tube 1 and between the head 11 of the bolt and the inner tube 2 are disposed washers 12—12, each having, as shown in Fig. 2, a curvilinear face conforming to and bearing against the circumference of the tube.

It will thus be noted, that when the nut 10 is loosened, the tubes 1 and 2 may be moved relative to each other to lengthen or shorten the gun-attaching portion of the 100

shoulder-rest, and that the tubes may be secured in the desired adjusted position by tightening the clamping nut.

The inner tube 2 is suitably secured to a standard 13 (shown in detail in Figs. 5 and 6) which, from the standpoint of practicability in manufacturing and lightness in weight, is preferably of sheet metal cut out and bent up from a single blank, and the longitudinal over-lapping ends 14—14 welded together.

Two opposite sides of the elongated hollow sheet metal member thus formed are bent or crimped in, as shown in Fig. 6, to provide two longitudinally-extending channels or slide-ways 15—15 to guide a slide 16, constituting the shoulder-rest piece (hereinafter more particularly referred to), in its movement on said standard 13. Each of said crimped-in portions is provided with a longitudinally extending slot 17, for a purpose presently appearing.

Each crimped-in portion, at each end thereof, carries a tongue or lip 18, the two tongues, at each end, being bent toward each other so that their free ends meet, as clearly shown in Fig. 6. Such meeting ends may be welded together. By this peculiar construction, the hollow standard is braced and strengthened against collapse or buckling inward of the walls thereof. It will be noted that the standard 13 is in one piece and that it is simple and practical from a mechanical standpoint, being easy and cheap to manufacture and light in weight, while possessing the requisite strength and durability.

The means for securing the tube 2 to the standard 13 may obviously be variable. An exceedingly simple and efficient form is shown in the drawings and will now be described.

A collar 19 (shown in detail in Fig. 11) is provided with a lateral circumferential flange 20, which may be welded to a side wall of the standard 13. The collar may obviously be threaded interiorly, and, in such case, the tube 2 would, of course, be exteriorly threaded at its end, so that it may be screwed into the collar. However, I prefer to make the collar unthreaded and to slide the end of the tube 2 therein, and then weld the collar thereto.

Adjustably supported on the standard 13 is the slide 16, constituting the shoulder-rest piece, shown in detail in Figs. 7 and 8. The slide is preferably formed from a single piece of material and comprises two side walls, which are crimped or bent inward, as shown, to form longitudinally-extending ribs or tongues 21—21, which fit in the complemental slide-ways 15—15 in the standard 13, whereby the shoulder rest piece is guided in its sliding movement on

the standard. The shoulder-rest piece is provided with a wing 22 having a curvilinear face 23, to fit the shoulder of the user, and which face may be transversely serrated, or otherwise roughened, to prevent slipping when the shoulder-rest piece is in use.

The crimped-in portions 21—21 are provided with diametrically opposite perforations 24, through which projects a threaded clamping bolt 25 carrying a wing nut 26, and which bolt passes through the slot 17 in the standard 13, whereby the ribbed portions 21—21 of the slide may be tightly clamped against the standard and the slide or shoulder-rest piece thereby securely frictionally held in adjusted position.

Having described my invention, what I claim as new and desire to secure by Letters Patent, is:—

1. A shoulder rest comprising a gun attaching portion adjustable with reference to length, a standard carried thereby positioned transversely thereof, and a slide, constituting a shoulder-rest piece, adjustably supported on said standard. 91

2. A shoulder-rest comprising a gun attaching portion in two telescoping sections positioned transversely thereof, a standard carried by one of said sections, and a slide, constituting a shoulder-rest piece, adjustably supported on said standard. 92

3. A shoulder-rest comprising a gun attaching portion in two telescoping sections, one of said sections being provided with a longitudinal slot extending from one end thereof, and with a second longitudinal slot, clamping means encircling said first mentioned slotted portion for contracting the same around a gun, clamping means passing through said second slot and through the other section for securing said sections in adjusted position, and a standard transversely carried by one of said sections, and a slide constituting a shoulder-rest piece adjustably supported on said standard. 10

4. A shoulder-rest comprising a standard formed from a single sheet metal blank and bent longitudinally to provide side walls, two of said walls being bent inwardly to provide longitudinally extending channels, 11 a slide, constituting a shoulder-rest piece, having complemental bent portions engaging said channels, and means for holding the slide in adjusted position on said standard. 11

5. A shoulder-rest comprising a standard formed from a single piece of metal and bent longitudinally to provide side walls, two of said walls being bent inwardly to form longitudinally extending channels; means for bracing said standard against collapse, comprising tongues carried thereby and bent toward each other with their free ends abutting; a slide having comple- 121

mental bent portions engaging said channels; and means for holding said slide in adjusted position on said standard.

6. A shoulder-rest comprising a standard 5 formed from a single piece of metal and bent longitudinally to provide side walls, the longitudinal edges of said blank being overlapped, two of said walls being bent inwardly to provide longitudinally extending

channels; means for bracing said standard 10 against collapse, comprising tongues carried thereby and bent toward each other with their free ends abutting; a slide having complementary bent portions engaging said channels; and means for holding said slide in 15 adjusted position on said standard.

SAMUEL G. GREEN.
